UNITED STATES PATENT OFFICE

2,242,342

SIGN

Rea M. Bruner, Houston, Tex., assignor of one-third to R. A. Kenley and Allan Murphy, both of Houston, Tex.

Application April 26, 1939, Serial No. 270,139

2 Claims. (Cl. 40—132)

This invention relates to signs particularly for use at street intersections, railway crossings, and other locations, for controlling traffic, and has for its principal object to provide a device of this character which is prominent and commanding in appearance.

Other objects of the invention are to provide a sign having a simple, rigid construction; to provide a sign having novel features for promoting safety and reducing crossing hazards; to provide a sign structure in which street signs and advertisement features are incorporated with stop and go signals; and to provide means for synchronizing illumination of the advertisement in timed relation with the stop and go signals.

In accomplishing these and other objects of the invention, I have provided improved details of structure, the preferred form of which is illustrated in the accompanying drawings, wherein:

Fig. 1 is a perspective view of a sign constructed in accordance with the present invention.

Fig. 2 is a similar view showing parts thereof in disassembled spaced relation.

Fig. 3 is a vertical section through the upper portion of the sign showing the relation of the various light compartments and the arrangement of the light sources therein.

Fig. 4 is a side view of the upper portion of the sign.

Fig. 5 is a horizontal section on the line 5—5 of Fig. 1.

Fig. 6 is a horizontal section on the line 6—6 of Fig. 1.

Fig. 7 is a wiring diagram of the light circuits used in connection with the sign.

Referring more in detail to the drawings:

1 designates a sign constructed in accordance with the present invention and which includes a post 2 which may be of rectangular cross-section as shown and have a hollow, upper portion forming a vertically arranged light compartment 3.

Formed in the front and rear sides 4 and 5 of the post, in registry with the compartment 3, are elongated openings 6 and 7 through which sign panels 8 and 9 are illuminated. The panels 8 and 9 may be formed of translucent material having letters 10 designating the name of the street or the like at which the sign is installed. The letters 10 may be formed as an integral part of the panels which are illuminated upon energization of the light bulbs 11 and 12 that are conveniently supported in the light compartment. The bulbs 11 and 12 are carried in sockets

13 and 14 provided with reflectors 15 and 16 arranged to direct the light rays longitudinally of the compartment and through the respective panels. The panels are retained in position over their respective openings by frames 17 and 18 extending around the margins thereof and secured by suitable fastening devices such as screws 19 extending through openings 20 in the frame and into threaded sockets 21 of the post as best shown in Figs. 2 and 6.

Carried upon the upper end of the post 2 is a rectangular box-like compartment 22. The compartment 22 substantially conforms to the thickness of the post and has its front and rear walls provided with openings 23 and 24 which are covered by panels 25 and 26 retained by frames 27 and 28 in the same manner as the post panels previously described. These panels are also preferably of translucent material and have lettering or other designations therein as indicated at 29 to form an advertisement.

The compartments 22 and 3 communicate through an opening 30 normally closed by a plate 31 which may be utilized as a support in carrying the upper lamp 11. Located in the respective corners of the compartment 22 are light bulbs 32, 33, 34 and 35 carried in sockets similar to those previously described. The light rays from the lamps are directed through the respective panels by substantially trough-shaped reflectors 36 and 37 extending vertically of the side walls 38 of the compartment as best shown in Figs. 3 and 5.

Supported on the top of the compartment 22 is a compartment 39 having flat front walls 40 and 41 provided with circular openings 42 and 43. The side walls 44 and 45 preferably curve upwardly and inwardly from points spaced from the side walls of the compartment 22 as best shown in Fig. 3, the upper edges of the respective walls being shaped to conform to the contained angle of a cross-like compartment 46, later described.

The openings 42 and 43 are covered by lens-shaped panels 47 and 48 formed of translucent material in the manner of the lenses of an ordinary stop light and carry the word "go." These panels are preferably green in color to conform with standard traffic signals. The lenses are secured over the openings by circular frames 49 and 50 retained in position similarly to the other panels previously described.

Supported in the compartment 39, in the apex thereof, is a light socket 51 carrying an electric bulb 52 for illuminating the "go" lenses, the rays from the bulb being directed against the lenses

by a suitable reflector 53. The connection between the compartments 22 and 39 is closed by a plate 54.

The cross-shaped compartment 46 includes angularly directed hollow arms 55, 56, 57 and 58, of rectangular cross-section, and radiating from a common center. These arms are provided with intersecting openings 59 and 60 in the respective front and rear faces thereof to receive cross-shaped lenses 61 and 62 retained by frames 63 and 64 secured by fastening devices similarly to the other frames. Supported in the ends of the respective arms are sockets 66 carrying light bulbs 67, 68, 69 and 70 respectively to illuminate the designations "stop" on the respective cross-shaped lenses as shown in Fig. 1.

In Fig. 7 I have illustrated the circuit for the respective light bulbs. The circuit includes main conductors 71 and 72 leading from a source of current supply such as a service connection, if one is available, or from a battery where the signal is located in remote places. The main conductor 72 connects with one of the terminals of all of the light bulbs; however, the conductor 71 connects with conductors 73, 74, 75 and 76 through single pole magnetic switches 77, 78, 79 and 80 respectively. The conductor 73 is connected with the other terminals of the lamp bulbs 11 and 12 which illuminate the street signs. The conductor 74 connects with the other terminals of the light bulbs 32, 33, 34 and 35 which illuminate the sign compartment. The conductor 75 connects with the other terminal of the light bulb 52 illuminating the "go" compartment, and the conductor 76 connects with the other terminals of the light bulbs 67, 68, 69 and 70 illuminating the cross-shaped "stop" panels. The switches 77, 78, 79 and 80 are activated by circuits including separate lines 81, 82, 83 and 84 including a common line 85 which connect with a standard municipal or other controlled traffic system, or a suitable individual, automatic timing switch as indicated by the housing 86. The circuits may be so timed that the "stop" and "go" are rendered alternately effective and may be timed for intervals depending upon the extent of traffic at the corner at which the signal is located. The circuits which connect with the lamp bulbs illuminating the advertising sign compartment may be connected to be energized during the interval between changes of the "stop" and "go" signals in the same manner as conventional "warning" signals commonly employed in connection with the customary "stop" and

"go" lights now in use. The advertisement letters are therefore preferably of amber color since they serve the purpose of the warning light of a standard signal. The same may be true of the lamp bulbs illuminating the street signs or the street signs may be operated continuously. In the latter instance they are preferably of different color, for example yellow.

From the foregoing it is obvious that I have provided a traffic sign which is of prominent and commanding appearance, of strong, rigid construction, and well suited for safety purposes. It is also obvious that I have provided a combination traffic control signal street and advertising sign wherein the sign feature is coordinate with the "stop" and "go" signals without interference with the effectiveness thereof.

What I claim and desire to secure by Letters Patent is:

1. In a sign of the character described, a post, a housing supported by the upper end of said post having circular openings on opposite sides thereof, panels covering said circular openings adapted to carry indicia representing a traffic signal, an X-shaped housing mounted on the upper end of the housing which has the circular openings, said first named housing being connected with a pair of arms of said X-shaped housing and being arranged within the contained angle of said arms, said X-shaped housing having openings on opposite sides thereof, panels covering the openings in said X-shaped housing adapted to carry indicia representing a traffic signal related to the first named traffic signal, and means for illuminating said panels at predetermined intervals relative to each other.

2. In a sign of the character described, a post, a housing supported by said post having openings on opposite sides thereof, panels covering said openings adapted to carry indicia representing a traffic signal, an X-shaped housing mounted on the upper end of the housing which has the openings, said first named housing being connected with a pair of arms of said X-shaped housing and being arranged within the contained angle of said arms, said X-shaped housing having openings on opposite sides thereof, panels covering the openings in said X-shaped housing adapted to carry indicia representing a traffic signal related to the first named traffic signal, and means for illuminating said panels at predetermined intervals relative to each other.

REA M. BRUNER.
